J. C. Conover

By *Clarence O'Brien*,
Attorney

UNITED STATES PATENT OFFICE.

JOHN C. CONOVER, OF SOMERVILLE, NEW JERSEY.

GUIDE FOR MOLDER TABLES.

Application filed January 8, 1927. Serial No. 159,984.

The present invention relates to a guide or fence and has for its prime object to provide a structure of this nature which is clamped on top of the shaper or variety 5 molder table to guide the work as it passes the cutter.

An important object of the invention lies in a structure of this nature which is adjustable without stopping the machine and within 10 out the necessity of adjusting the knives.

Another important object of the invention lies in the provision of a device of this nature which is simple in its construction, inexpensive to manufacture, thoroughly efficient 15 and reliable in use, and otherwise well adapted to the purpose for which it is designed.

With the above and numerous other objects in view as will appear as the description proceeds, the invention resides in certain 20 novel features of construction, and in the combination and arrangement of parts as will be hereinafter more fully described and claimed.

In the drawing:—

25 Figure 1 is a perspective view of the guide showing the same mounted on a table, and

Figure 2 is a sectional view taken substantially on the line 2—2 of Figure 1.

Referring to the drawing in detail it will 30 be seen that 5 denotes the table on which is mounted a bracket 6 extending longitudinally thereof and having the overhanging flange 7 provided with a plurality of longitudinally extending slots 8. Numerals 9 denote plates having bolts rising therefrom through slots 8, said bolts being denoted by numerals 10, and having nuts 11 threadedly engaged thereon so that the plates 9 may be held in different adjusted positions in respect to each other.

The adjacent ends of the plates 9 have like corners cut away to form spaces as is shown at 12 for the rotary cutter 14 which has collars 15 mounted thereon for holding 45 the cutting tools 16 therebetween. The forward edges of these plates 9 are provided with flanges 17 rising therefrom and the outer ends thereof are bent forwardly at right angles to provide extensions 18. Wedge 50 blocks 19 have their inclined faces slidable on the flanges 17 and projecting therefrom are provided with bolts 20 extending through longitudinal slots 21 in the flanges 17 and having nuts 22 threadedly engaged there-

with. Adjusting screws 23 are threaded 55 through the extensions 18 and engaged in plates 25 held on the outer ends of the blocks 19 by screws 26 or in any other suitable manner. Thereby, the screws 23 may be turned for adjusting the blocks 17 toward or away 60 from each other. As the blocks are moved toward the center of the table it will be apparent that they move closer to the edge 30 of the table 5.

In using this device the work is held 65 against the guide block 19 to the right of Figure 1 and is fed up to the cutter. If the depth of the cut is too much, the adjusting screw 23 is manipulated to push the block toward the cutter. After passing the cutter 70 the other block is adjusted to line with the finished work and holds the work in line and straightens the same. Thus the adjustment may be made while the cutter is in operation 75 thus simplifying the process and saving much time.

It is thought that the construction, utility, operation, and advantages of this invention will now be apparent to those skilled in this art without a more detailed description 80 thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the 90 invention as hereinafter claimed or sacrificing any of its advantages.

Having thus described the invention, what I claim is:—

1. In combination, a pair of plates, means 95 for adjustably mounting the rear aligned edges of the plates on a table for movement in alignment with each other, flanges rising from the forward edges of the plates and having angular extensions, wedge blocks 100 having their inclined faces slidable on the flanges, pin and slot means engaging the blocks on the flanges, and screw means associated with the extensions and the blocks for moving them along the flanges.

2. In combination, an angular bracket 105 adapted to be attached to a table and having longitudinal slots, plates, bolts rising from

along the rear edges of the plates through the slots, nuts on the bolts to hold the plates in adjusted relation to each other, flanges rising from the forward edges of the plates, 5 wedge blocks having their inclined faces slidable on the flanges, pin and slot means engaging the blocks on the flanges, angular

extensions at the outer ends of the flanges, screws threaded through said extensions, and means swivelly engaging the screws 10 with the outer ends of the blocks.

In testimony whereof I affix my signature.

JOHN C. CONOVER.
